UNITED STATES PATENT OFFICE.

JOHN S. DAVIS, OF SPOKANE, WASHINGTON, ASSIGNOR TO HATTIE E. DAVIS, OF SPOKANE, WASHINGTON.

ARTICLE CARRIER.

Application filed June 7, 1921. Serial No. 475,816.

To all whom it may concern:

Be it known that I, JOHN S. DAVIS, a citizen of the United States, residing at Spokane, in Spokane County, and State of Washington, have invented certain new and useful Improvements in Article Carriers, of which the following is a specification.

My present invention relates to improvements in article carriers of the hand type, 10 designed especially for use in carrying milk bottles and convertible for use in carrying packages, boxes etc in connection with a cord or chain.

The primary object of the invention is 15 the provision of a package or article carrier of this type which is hand supported and particularly adapted for applying to the neck of a milk bottle. By the utilization of my invention as embodied in the 20 device hereinafter described the bottle may be held in one hand and the device applied thereto with facility while grasped in the other hand, and the loop for embracing the neck of the bottle may be adjusted to various 25 sizes of necks.

The invention consists in certain novel 30 combinations and arrangements of parts whereby a comparatively inexpensive device of this character may be manufactured in large quantities and either sold directly to 35 users or given away as advertising novelties, and to this end involves a minimum number of parts of simple construction, rendering the device durable, and facile in manipulation and use.

In the accompanying drawings I have 40 illustrated one complete example of the physical embodiment of my invention wherein the parts are combined and arranged according to the best mode I have thus far devised for the practical application of the principles of my invention.

Figure 1 is a perspective view illustrating the device in use as a milk bottle carrier, 45 showing also in dotted lines the position of parts when applying the device to the bottle.

Figure 2 is a perspective view of the device in position for use.

Figure 3 is a perspective view showing the 50 converted carrier applied for use in connection with a cord about a box of fruit, illustrating the manner of carrying a package.

In the preferred form of the invention as illustrated in the drawings I have utilized 55 a bottle B of the type used for delivering

milk and provided with a ribbed neck N with which the device of the invention is designed to co-act when carrying the bottle.

The carrier is preferably made of non-rusting metal as galvanized iron wire and 60 the handle, in the form of a U-shape bail is composed of two pieces 1 and 2 having their ends bent at right angles thereto, flattened as at 3 and 4, and these ends are welded or soldered together by suitable process or 65 tools as shown.

The rigid flattened ends 3, 4, not only form a handle to the bail, to be held in the hand for carrying the article, but they also form means for receiving advertising matter or identification data which may be stamped thereon in suitable dies when the 70 ends are flattened to form the hand-grasp of the handle or bail.

At their lower ends these wire pieces 1 75 and 2 of the bail are bent at an angle at 5 and 6 respectively and then fashioned with curved arms 7 and 8 to form a portion of a loop as shown. One of these arms is bent or offset as at 9, and the ends 10 and 80 11 of the arms overlap as shown in Figure 2 to provide a continuous loop, which because of the fact that the wire arms of the loop are of resilient formation, adapt the loop for extension or contraction and permit the loop to adjust itself to bottle-neck 85 of various sizes.

A third member 12 is utilized to complete the loop which is flattened as shown and may have stamped thereon suitable inscriptions for advertising or identification. This portion of the loop is also U-shaped, and its curved arms terminate in bends 13, 13 which merge into return bends 14, 14 to form a loop about the handle arms 1 and 2 at their 95 bends 5 and 6. A right angle bend 15 is formed on the return bends 14, and these bends 15 terminate in sharpened prongs 16 projected downwardly from the final bends 15, to be utilized for insertion into the 100 bottle cap or stopper for removing the latter.

It will be noted that the U-shaped portion 12 and the curved arms 7, 8 form a complete loop, and the bends in the U-shape portion 105 12 provide retaining slots about the lower ends of the handle or bail, whereby the loop may fit up under the bead at the neck of the bottle as in Figure 1, and the bail be utilized as a handle for carrying the bottle 110

thus supported. The U-shape portion 12 of the loop is supported by its slotted ends on the bail, and the arms 1 2 of the bail may be slipped down through these slots in order 5 that the space between the loop portions may be elongated and in this position the carrier may readily be slipped over the top of the bottle as in dotted lines Figure 1. After slipping the device over the bottle 10 neck, the handle 3-4 is grasped and the bail pulled upwardly bringing the two portions of the loop up under the opposite sides of the bead of the bottle to complete the circular loop and provide a support for the 15 bottle through its bead, the handle being employed to carry the bottle in an upright position without danger of spilling its contents. In this position the bail or handle is retained in a symmetrical position in a 20 vertical plane at right angles to the horizontal plane of the complete loop, and the prongs 16 which also stand in a vertical plane parallel with the handle bars of the bail are frictionally engaged with the bottle 25 neck to aid in holding the device in stable position.

By the utilization of a cord C a package or box F may be carried, in which case the 30 cord is passed around the package, over the bends 5 and 6 of the handle bars and between these bends and the bends 13 of the loop portion 12. The arms 7 and 8 lie flat on the top of the box, but because of the 35 prongs 16, whose ends rest upon the top of the box, the loop portion 12 is tilted upwardly with the bends 13 at the highest point of this loop portion 12, to form retaining means for the cord and prevent its displacement from the carrier. As shown 40 in Figure 3 the carrier may thus readily be applied for carrying boxes or packages and the bail or handle utilized in usual manner for carrying the package.

The three parts composing the carrier are stamped or fashioned in suitable machines 45 or by the use of proper tools, and as before stated the slotted connection between the handle portion and the loop portion of the device permits ready application of the device over the bottle neck at which time the 50 device is held by the hand grasping the handle bar 3-4. The device is retained in place by frictional contact and resiliency of the loop, and in Figure 1 it will be apparent that by first pushing down on the handle 55 or bail and swinging the bail to the right, the connection between the bail and loop may be sufficiently loosened to permit ready withdrawal of the carrier when not to be used. 60

Having thus fully described my invention, what I claim as new and desire to secure by Letters Patent is—

1. The combination in a carrier as described with a bail having angularly disposed complementary curved arms of resilient metal and overlapping ends, of a U-shaped loop portion complementary to said arms, said loop portion having return bends forming slots about the junction of 70 the bail with its arms.

2. The combination in an article carrier with a bail having a flattened handle bar and angularly disposed curved arms one of which is provided with an off-set, said arms 75 composed of resilient wire and fashioned with overlapping ends, of a complementary U-shaped loop portion having return bends forming slots about the junction of the bail with its angular arms, and said return bends 80 having downwardly projecting prongs at their extremities.

In testimony whereof I affix my signature.

JOHN S. DAVIS.
